ADJUSTABLE CRADLE FOR WEFT REPLENISHING LOOMS

Filed May 4, 1925

Patented Nov. 30, 1926.

1,608,652

UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

ADJUSTABLE CRADLE FOR WEFT-REFLENNISHING LOOMS.

Application filed May 4, 1925. Serial No. 27,638.

This invention relates to improvements in the construction of cradles for weft replenishing looms of the multi-color type and an object of the invention is to provide a cradle 5 of variable length to be used with long or short bobbins.

A further object of the invention is to provide a multi-part bobbin cradle having two sections which slidably interengage with 10 each other and are held together by removable means which permit relative adjustment to lengthen or shorten the cradle.

With these and other objects in view which will appear as the description proceeds, my 15 invention resides in the combination and arrangement of parts hereinafter described and set forth in the claims.

In the accompanying drawings wherein I have shown a convenient embodiment of my 20 invention,

Fig. 1 shows the inner and outer plates of a multi-color weft replenishing mechanism provided with my improved cradle and indicates how the outer plate can be adjusted 25 for different lengths of bobbins,

Fig. 2 is a perspective view of my improved cradle,

Fig. 3 is a fragmentary front elevation of the adjustable portions of the cradle,

Fig. 4 shows one end of the section which 30 engages the butt of the bobbin,

Fig. 5 is a view similar to Fig. 4 but showing the end portion which engages the tip of the bobbin, and

Figs. 6 and 7 are vertical sections on lines 35 6-6 and 7-7 of Fig. 3, respectively.

Referring more particularly to the drawings it will be seen that I have provided a magazine of the multi-color type such as is set forth in prior Patent No. 1,030,748 and having an inner plate 10 provided with a plurality of vertical guideways for the heads of the bobbins and having another plate 11 also provided with guideways for the tips of the bobbins. The guideways separate the bobbins into vertical stacks according to color, the bobbins being moved downwardly one at a time to transfer position. At the bottom of each stack of bobbins is located a so-called cradle 12 which acts as a gate to pass one bobbin at a time from the stacks to the yielding giveways 13 such as those shown in Patents No. 1,366,950 and No. 1,495,717. In the normal operation of the replenishing

mechanism the cradle is empty and at indication of weft exhaustion by the weft detector the cradle is rocked to receive a bobbin. When the indicating shuttle returns to the magazine side of the loom the cradle is given a return movement to its normal position and discharges the bobbin. The plate 11 is adjustably mounted on tie rods 14 extending from plate 10 and can be moved on said rods toward or from said plate 10.

It is occasionally desirable to vary the length of the bobbin used in a loom and under these conditions it has heretofore been necessary to take out the old cradles and insert an entirely new set. This change involves adjustment of the ends of the new 70 cradles and also necessitates two complete sets of cradles. In order to avoid the settings and adjustments necessary when new cradles are inserted in the magazine and also to avoid the necessity for having an extra set 75 of cradles I propose to make each cradle in two sections which shall have interengaging portions to permit the length of the cradle to be varied.

Accordingly in carrying out my invention 80 I provide two cradle sections 20 and 21 which engage the butt and tip, respectively of the bobbins. The section 20 has a bobbin supporting finger 22, bearing 23, and a pin 24 by means of which the cradle is oscillated. The 85 section 21 is also provided with a bearing 25 and has a nose 26 which engages the tip of the bobbin to regulate the movement of the same toward transfer position. The section 20 has the end 27 thereof provided with a 90 tongue 28 which extends to that end of the section 20 remote from the bearing 23. The section 21 is provided with a groove 29 proportioned to fit snugly over the tongue 28. The tongue 28 and groove 29 are substantially parallel to the axis of the cradle. A slot 30 extends longitudinally of the section 21 and is proportioned to receive holding screws 31 which extend through the slot into tapped holes 32 in the tongue 28 to hold the 100 two sections together firmly.

The cradle is shown in its greatest length in the drawings and when it is desired to shorten the same the screws 31 can be loosened and fitted into the proper threaded 105 holes 32 and the sections adjusted until the desired length is obtained, after which the screws 31 can be tightened.

Fig. 6 shows the portion of section 20 which is adjacent the bobbin to be concave as at 33 and the section 21 extends in front of said concave surface so as not to interfere with the full bobbin.

In Fig. 1 the plate 11 is shown in full lines in the position it assumes when the cradle 12 is at its greatest length and the dotted lines show the position said plate assumes when the cradle is shortened. Tie rods 14 support the plate 11 and can be used for all adjusted positions thereof.

From the foregoing it will be seen that I have provided an adjustable cradle formed of two sections with overlapping portions which can be securely fastened together to be used with bobbins of various lengths. It will also be seen that when the ends of the cradle are adjusted for any particular magazine frame they can be used for different lengths of bobbins without requiring new adjustments when a different length of bobbin is used. It will further be noted that the tongue and groove connection between the sections maintains the same angular position of the ends of the section for all adjusted lengths thereof.

Having thus described my invention it will be apparent that changes and modifications may be made therein by those skilled in the art without departing from the spirit and scope of the invention, and I do not wish to be limited to the details herein disclosed but what I claim is:

1. In a bobbin replenishing mechanism for looms, an inner plate for the heads of bobbins, an outer plate for the tips of bobbins, means to hold said plates in adjusted spaced relationship, means formed on said plates defining a guideway for bobbins, and a discharge device located at the bottom of the guideway and supported by said plates and extending therebetween and formed of two parts, one for the heads and one for the tips of the bobbins, said parts being held together in any one of a plurality of positions to render the device capable of assuming a plurality of lengths depending upon the distance between said plates.

2. In a bobbin replenishing mechanism for looms, an inner plate fixed with respect to the loom, an outer plate adjustably spaced from the inner plate, means formed with said plates defining a guideway for the bobbins, and an extensible discharge device located at the bottom of the guideway formed of two parts, one for the heads and one for the tips of the bobbins, said parts

being held together in any one of a plurality of positions to render the device capable of assuming a plurality of lengths depending upon the adjusted distance between said plates.

3. In a bobbin replenishing mechanism for looms, a fixed inner plate, an outer plate, means extending between said plates to space the same in adjusted positions, means carried by said plates defining a guideway for the bobbins, and an extensible discharge device located at the lower end of the guideway, and having a part to engage the heads and another part to engage the tips of the bobbins, said parts being connectable together in different positions to render the device of variable length to extend between the plates in all adjusted positions thereof.

4. A loom weft replenishing mechanism cradle formed in two parts slidable on each other, complementarily formed guide means on said parts, and means to hold said parts together in adjusted position, one of said parts being formed to receive the butt of a bobbin and the other part being formed to receive the tip of a bobbin.

5. A loom weft replenishing mechanism cradle formed in two parts, one of said parts having a rib substantially parallel to the axis of the cradle and the other part having a complementarily formed slot to receive the rib, said slot also being substantially parallel to the axis of the cradle, and means to secure said parts together in adjusted longitudinal position.

6. A loom weft replenishing mechanism cradle having two parts, one part formed to act on the tip of a bobbin and the other part formed to act on the butt of a bobbin, said parts having overlapping portions and adjustable connections extending through the overlapping portions to hold the parts together in any one of a plurality of positions.

7. A loom weft replenishing mechanism cradle having two parts, one part formed to act on the tip of a bobbin and the other part formed to act on the butt of a bobbin, and means to secure said parts together in any one of a plurality of longitudinally adjusted positions, said means preserving the same relative angular position with respect to said parts for all longitudinally adjusted positions thereof.

In testimony whereof I have hereunto affixed my signature.

ALBERT A. GORDON.
